CLAIM

The ornamental design for tray with cover, as shown and described.

DESCRIPTION

FIG. 1 is a perspective view of a tray with cover in an opened position;

FIG. 2 is a front view of the tray with cover, as shown in FIG. 1, showing the tray with cover in a closed position, the back view being an identical image thereof;

FIG. 3 is a top view of the tray with cover, as shown in FIG. 2;

FIG. 4 is a bottom view of the tray with cover, as shown in FIG. 2; and,

FIG. 5 is a right side view of the tray with cover, as shown in FIG. 2, the left side view being an identical image thereof.
